UNITED STATES PATENT OFFICE.

GEORGE RITTER, OF WOODBRIDGE, NEW JERSEY, ASSIGNOR TO THE BARBER ASPHALT COMPANY, OF PHILADELPHIA, PENNSYLVANIA, A CORPORATION OF WEST VIRGINIA.

SHINGLE.

Application filed October 26, 1923. Serial No. 670,811.

This invention relates to improvements in shingles, the principal object of the invention being to provide a shingle which is adapted to cooperate with the nail that is commonly used for securing the shingle in place, in such a manner that without the use of any other holding device the shingle will be efficiently held against removal, but at the same time is permitted to expand and contract with changes of temperature, so that "buckling" of the shingle is avoided.

A further object of the invention is to provide a shingle having an underlying portion or flap and a correspondingly shaped recess so located that a pair of shingles may be nested or mated together in such manner as to present at each side thereof a surface lying in a single plane, whereby a plurality of the shingles may be packed for shipment without any spaces between them, whereby the liability of injury to the shingles during transportation is minimized.

With the foregoing and other objects in view, which will appear as the description proceeds, the invention consists in the novel features of construction and combination of parts which will be more fully described hereinafter and particularly pointed out in the claims.

In the drawings accompanying and forming part of this specification,

Fig. 1 is a plan view of a portion of a roof covered with shingles constructed and laid in accordance with the present invention;

Fig. 2 is a sectional view taken on the line 2—2 of Fig. 1;

Fig. 3 is a plan view of a shingle, illustrating the same scored to form a flap, the dotted lines indicating the operative position of the flap;

Fig. 4 is a sectional view taken on the line 4—4 of Fig. 3;

Fig. 5 is a fragmentary plan view, on a larger scale, showing the underside of a shingle and illustrating the flap secured in its operative position with a clearance space provided for the head of the fastening nail;

Fig. 6 is a sectional view taken on the line 6—6 of Fig. 5;

Fig. 7 is a side view, partly in section, illustrating a plurality of shingles packed together for shipment;

Fig. 8 is an underside plan view showing a modified form of shingle; and

Fig. 9 is a fragmentary underside plan view of a shingle, illustrating a different form of nail-engaging opening in the flap.

The same characters of reference designate the same parts in the different figures of the drawings.

Referring to the drawings, 1 designates my improved form of shingle, which may be of the flexible variety usually made of a belt base saturated and coated with bituminous material and having a mineral surface, or it may be of the stiff variety such as those known as asbestos shingles.

In the present instance the shingle 1 is provided, preferably at one corner thereof, with an underlying portion or flap 2, forming a double thickness at this point. In the flap 2 is formed an opening adapted to permit the shingle 1 to engage a suitable fastening device, such as the usual shingle nail 3, having a head 4 of considerably greater diameter than the shank. In the form shown in Figs. 3 to 6 and 8, the opening 5 is of key-hole form; that is to say, it is of sufficient width at one portion thereof to permit the passage of the nail head 4 therethrough, while the remaining portion of the opening is comparatively narrow, so that when the underlying flap 2 is placed in engagement with the nail 3 and the shingle 1 moved backward until the shank of said nail is in the narrower portion of the opening 5, said shingle cannot become disengaged from said nail. In Fig. 9 I have shown the end or apex of the flap 2 cut away to form an open-ended slot 5*, by means of which the shingle may be more readily placed in engagement with the nail 3, as will be hereinafter more fully described.

When the shingle 1 is of the flexible variety, a convenient method of providing the underlying flap 2 is to score the shingle diagonally across one corner thereof, as illustrated at 6 in Figs. 3 and 4. It will be seen from said figures that the scoring 6 is of considerable depth, but leaves sufficient material to prevent separation of the flap 2 from the body of the shingle 1. The danger of loss of the flap 2 before the same is secured in place is thus avoided. After the flap 2 has been thus scored off, it is bent along the scored line 6 and pressed on to the underside of the shingle body 1, heat being applied during the pressing operation 110

thereby to cause the flap 2 to firmly adhere to that portion of the body of the shingle 1 in contact therewith. Provision is made to avoid heating the flap 2 along the edges of the opening 5 in order to leave that portion of the flap 2 separated from the body of the shingle 1, as illustrated at 7, so as to provide a clearance space for the nail head. In the case of flexible shingles the flap 2 is thus securely fastened to the shingle 1 without the use of any adhesive material other than that incorporated in the shingle itself. When the shingle 1 is of the stiff or asbestos variety, however, it is necessary to insert an adhesive between the flap 2 and the shingle body.

It will be readily understood that the invention is not confined to a shingle 1 of any particular shape, but may be applied to any shingle regardless of its shape. For instance, in Fig. 8 the shingle 1^a is shown of diamond shape, its flap 2^a being correspondingly modified.

The shingle 1 is formed with a recess 8 disposed diagonally opposite the flap 2, and this recess corresponds in shape with said flap. One of the objects for which this recess 8 is provided is to enable the shingles to be packed together for shipment without forming any spaces between them. In Fig. 7 is clearly illustrated the manner in which the shingles 1-1 are nested or mated. It will be noted that the flap 2 of one shingle enters the recess 8 of its next adjacent shingle, and vice versa, so that the flaps 2-2 as well as the shingles 1-1 are properly protected during transportation. The recess 8, however, performs still another function, namely, it provides a means for accurately "lining up" the shingles 1-1 without the necessity of first marking off the sheathing of the roof as is usually done, since, when the shingles 1-1 are in their proper relative positions the side edges of the shingles of the outer course will be in alinement each with one wall of the recess 8 in the shingles which it overlies, as clearly indicated in Fig. 1.

In order to avoid any uncertainty as to the proper point at which the nail 3 should be placed, the shingle 1 is preferably provided during its manufacture with a hole 11, so that the carpenter is not left to guess as to the proper point to place the nail 3.

Referring now to Figs. 1 and 2, 9 designates the wooden sheathing to which the shingles are to be nailed. Along the lower edge of said sheathing 9 a starting strip 10 is nailed, said starting strip being preferably of double thickness and having triangular recesses formed in the upper layer at the proper distances apart to receive the underlying flaps 2-2 of the first course of shingles 1-1. A nail 3 is driven into said starting strip 10 midway between the walls

of each of said recesses, the nail, however, not being driven all the way down, a sufficient portion being left projecting above the strip to permit the flaps of the first course of shingles 1-1 to engage their respective nails 3-3 in such a manner that the head 4 of the nail passes into each space 7 extending along the edges of the opening in the flap 2. When shingles 1-1 having the form of opening or slot shown in Fig. 9 are used, each shingle is merely manipulated so that the shank of the nail 3 is guided into the widened end of the slot 5^a, whereupon said shingle is given a slight pull so as to carry the narrower portion of the slot beneath the head of the nail. The shingle 1 is then straightened so that its two side corners are in exact alinement with those of the adjacent shingles 1-1 of the same course, and a nail 3 is driven through the hole 11, said nail being left partly projecting above the shingle 1 as above described in order to engage with the flap 2 of the next overlapping shingle. In the case of shingles 1-1 having the keyhole form of opening 5, each shingle 1 is manipulated until the nail head 4 passes through the enlarged portion of said opening, whereupon the shingle 1 is pulled so as to carry the narrower portion of the opening below the nail head 4 in the manner above described. It will thus be seen that each shingle 1 is securely held in position by the use of two nails 3-3, while it is free to expand and contract without being liable to buckle or otherwise be injured.

I am aware that it is not new to provide a shingle with a folded under butt or flap. All shingles of this type, however, with which I am familiar are provided with other means, such as wires or bands inserted in the fold and forming a part thereof, for holding them down. My invention eliminates the use of any special attachments or accessories, and all that is required is the conventional type of large headed roofing nail, which when driven down into the shingle as shown in the drawings, in connection with either of the forms of opening or slot which I have shown in the corner fold or flap, provides a practical means for holding down the butt of the shingle and at the same time allowing for lateral or longitudinal expansion, compensating for the difference in the coefficients of expansion between the shingles and the roof deck, thereby eliminating the cause of so-called buckling of the shingles.

Having thus described my invention what I claim is:

1. A point-down shingle having a vertically disposed key-hole slot in the lower angular point, said angular point being retroverted and in part adhered to the body portion of the shingle.

2. A flexible shingle having a point-down vertically elongated slot in the lower part, said slotted part being retroverted and in part adhered below the main body of the shingle.
3. A flexible shingle having one of its corners formed with a key-hole slot and retroverted to provide a flap adhesively contacting in part with the body portion of said shingle to afford an intervening clearance for an attaching means.
4. A flexible shingle having one of its corners formed with an elongated slot and retroverted to provide a flap, said flap adhering in part to the body portion of said shingle thereby affording an intervening enclosure-clearance for the head of an attaching nail.
5. A point-down shingle having one of its corners formed with a key-hole slot and retroverted to provide an attaching flap, and a diagonally opposed notch in said shingle complementarily configured with respect to the retroverted flap, whereby the shingles may be evenly compacted for shipment. 20
6. A point-down shingle having one of its corners formed with a key-hole slot, and retroverted to provide an underfolded flap affording a clearance surrounding said key-hole slot, and a complementarily configured recess diagonally opposed to the aforesaid underfolded flap, for the purposes set forth. 25

Signed at Woodbridge in the county of Middlesex and State of New Jersey this 22nd day of October, A. D. 1923.

GEORGE RITTER.
